UNITED STATES PATENT OFFICE.

CHRISTIAN GIRL AND HERBERT S. JANDUS, OF KALAMAZOO, MICHIGAN; SAID JANDUS
ASSIGNOR TO SAID GIRL.

MACHINE FOR CAMBERING AND TEMPERING METAL.

Application filed March 13, 1922. Serial No. 543,490.

To all whom it may concern:

Be it known that we, CHRISTIAN GIRL and HERBERT S. JANDUS, citizens of the United States, residing at Kalamazoo, in 5 the county of Kalamazoo and State of Michigan, have invented a certain new and useful Improvement in Machines for Cambering and Tempering Metal, of which the following is a full, clear, and exact description, 10 reference being had to the accompanying drawings.

This invention relates to machines for shaping and tempering metal and more particularly to machines which are designed 15 for the cambering and tempering of spring plates.

As is well known, after the plates from which vehicle springs are formed, are shaped, they are tempered by being 20 quenched, preferably by immersion in oil. It is the object of the present invention to provide a cambering machine, for shaping the spring plates or like articles, with 25 improved means for performing the quenching or tempering operation, such means including an oil (or other liquid-containing) tank which is associated with and which preferably encloses the lower part of the cambering machine and in which the oil 30 may be raised and lowered in a convenient and effective manner, so that, when the level of the oil or other quenching liquid in said tank is raised, the spring plates will be immersed and quenched and, after the quenching operation, the oil level may be conveniently lowered to a level below that of said plates, permitting the plates to be removed 35 from the machine.

In the form of our invention shown here- 40 in the change in the liquid level is effected by means of a hollow body which is raised and lowered by a mechanical connection with the cambering machine, and in time with the movement of the ram of the latter, so 45 that, when the ram is lowered to form the spring or other article, the body is simultaneously lowered into the liquid, and when the ram is lifted, the hollow liquid-displacing body is also lifted.

50 In the accompanying drawings, Fig. 1 is a sectional elevation of a cambering machine embodying our invention; Fig. 2 a detail in section on the line 2-2 of Fig. 1; and Fig. 3 a front elevation of the apparatus shown in Fig. 1.

Referring specifically to the drawings, the cambering machine comprises generally a pair of vertical guide frames 1 supporting a shaft 2 having a pair of eccentrics 2^a thereon upon which are suspended, 60 by arms 3, the upper cambering head or ram. The shaft 2 is driven by a motor 4, the shaft 5 of which is mounted in brackets 5^a supported by the guide frames 1, the said shaft being provided with a pinion 5^b meshing with a gear 6 on the shaft 2. The upper head or ram 6^a of the cambering machine is suspended from the arms 3 and cooperates with the lower fixed head or anvil 6^b mounted in a tank, indicated generally at 7. The 70 lower head or anvil 6^b is mounted in the tank 7 below the top thereof, the said tank having therein oil (or other quenching liquid) normally at a level below the top of the form or anvil 6^b and below the level of 75 plate S applied thereto.

The oil level is raised and lowered by a displacing body which as shown consists of a hollow vessel or block 8 which may be raised and lowered in the tank behind or 80 beside the cambering machine. This body is connected by a rod 9 to a crank 10 on a shaft 11 which is turned in proper time by sprockets 12 and 13, a chain 14, and a half-stop clutch 15 mounted on the shaft. This half- 85 stop clutch may be of a known type, acting to turn the shaft 11 a half turn, and then stop the same with the crank, and consequently the body 8 in low position, the shaft being afterwards picked up and lifted in 90 time with the lift of the ram, the intent being to hold the oil level raised a sufficient time to accomplish the quenching operation.

Any other suitable mechanical means may be employed for effecting the same result. 95 The body or vessel 8 is preferably provided with trunnions 16 which slide between guides 17 secured to the opposite walls of the tank 7, thereby to give a straight-line movement to said body or vessel.

In operation, as stated, the oil level is normally below the forming elements of the cambering machine. When the ram descends, the body or vessel 8 is also forced down into the oil, displacing a volume thereof sufficient to raise the level of the oil in the tank and submerge the article clamped between said forming elements; after the article is quenched, the ram is lifted, together with the displacing vessel or body, and the 110

oil level lowers to its normal position for the next operation.

This construction provides a very simple and cheap mechanism for varying the oil level in the tank, for the purpose described. The substitution of other mechanical devices being possible, no limitation is implied by reason of the particular devices shown and described.

10 Having thus described our invention, what we claim is:

1. The combination, with a quenching tank, of a cambering machine supported therein, and means for mechanically displacing a volume of liquid in the tank to raise and lower the level thereof and quench an article held in the cambering machine.

2. The combination, with a quenching tank and a cambering machine supported therein, of means for mechanically displacing a volume of liquid in the tank to raise and lower the level thereof and quench an article held in the cambering machine, said means including a displacing body movable into and out of the liquid in the tank.

3. In a quenching apparatus, the combination of a liquid-containing tank, and a displacing body movable into and out of the liquid in the tank and of sufficient displacement to raise and lower the oil level in the tank by such movement.

4. The combination, with a cambering machine having forming elements, of a quenching tank the liquid level in which is normally below said elements, and a displacing body movable into and out of the liquid in the tank thereby to vary the level of the liquid in the tank, said body having an automatically operating connection with a movable element of the cambering machine.

5. The combination with a cambering machine having a forming ram, of a quench-

ing tank in which the machine is mounted, 45 the normal level of liquid in said tank being below said ram, a displacing body of liquid in said tank being below said ram, a displacing body movable into and out of the liquid in the tank thereby to raise and lower the level thereof, and means to automatically move said body in time with the movement of the ram, whereby the liquid level is raised when the ram is lowered, and vice versa. 55

6. The combination, with a cambering machine having a reciprocating ram and means to operate the same, of a quenching tank in which the machine is mounted, the liquid level in the tank being normally below the 60 ram, a displacing body movable into and out of the liquid in the tank to raise and lower the level thereof, and an operative connection between the body and the operating means for the ram whereby the body is 65 moved in time with the movements of the ram.

7. The combination, with a cambering machine having a reciprocating ram and means to operate the same, of a quenching 70 tank in which the machine is mounted, the liquid level in the tank being normally below the ram, a displacing body, movable into and out of the liquid in the tank to raise and lower the level thereof, an operating 75 connection between the body and the operating means for the ram adapted to move the body in time with the movements of the ram, and guides in the tank for the said body.

In testimony whereof, we hereunto affix our signatures in the presence of two witnesses.
